UNITED STATES PATENT OFFICE.

ARTHUR J. BRIGGS, OF SYRACUSE, NEW YORK, ASSIGNOR TO REMINGTON TYPEWRITER COMPANY, OF ILION, NEW YORK, A CORPORATION OF NEW YORK.

TYPE-WRITING MACHINE.

1,132,908.

Specification of Letters Patent. Patented Mar. 23, 1915.

Application filed April 17, 1914. Serial No. 832,475.

To all whom it may concern:

Be it known that I, ARTHUR J. BRIGGS, a citizen of the United States, and resident of Syracuse, in the county of Onondaga and State of New York, have invented certain new and useful Improvements in Type-Writing Machines, of which the following is a specification.

This invention relates to improvements in fractional line-spacing mechanisms, or platen-clutches, of typewriting machines, the main object of the invention being to produce a satisfactory platen-clutch of an especially simple and compact construction.

15 The invention consists of a clutch that has the features of construction hereinafter described and specified in the claims and that normally connects together a cylindrical platen and line-spacing wheel, but enables 20 the platen to be separately rotated when mounted as usual in a paper carriage.

In the accompanying drawings, in which like reference numerals designate like parts in the different views, Figure 1 is a front 25 view and vertical section of this clutch, and the line-spacing wheel and a fragment of the platen of a typewriting machine; Fig. 2, a perspective of the body of the clutch; Fig. 3, a perspective of the line-spacing 30 wheel; Fig. 4, a perspective of a case in which the line-spacing wheel fits; Fig. 5, a perspective of a part of the clutch; Fig. 6, an end view of the clutch and line-spacing 35 wheel, at the left of the plane x, x , Fig. 1; Fig. 7, a cross-section of the clutch on the plane y, y , Fig. 1; Fig. 8, a side view of the clutch, line-spacing wheel and fragment of the platen; and Fig. 9, an enlarged cross-section, on the plane z, z , Fig. 1, of the hub of 40 the finger-wheel and a push-rod within it.

The platen 1 is made fast as usual (preferably at the end not shown) to the platen shaft 2, comprising also the tubular part 3 in which are slots 4; and loosely fitted in 45 these slots is a block 5 which extends transversely through the tubular part 3, and is movable transversely and axially of the shaft but constrained to turn with it. The edges or surfaces 6 of this block (Fig. 7) are flat, except at its outer end where they curve as shown and form faces of small projections 7, and in the outer end of the block is a notch or recess 8. The inner end 9 of this block rests against a coiled spring 10 contained in the tubular part 3 of the shaft 2,

which latter may be of any suitable length, though only a small part of the solid portion 2 is illustrated. The spring 10 tends to force the block outward, or from the platen.

60 The body of the clutch comprises a slotted, cylindrical block, a head 11 and a hub 12, the slot forming recesses 13 and dividing the block into parts 14 and 15 which have surfaces 16 and 17, each being a part of a cylindrical surface. The head 11 has a flange 18 which extends outward from the surfaces 16 and 17. Two jamb blocks 19 and 20 fit loosely in the recesses 13, the outer surfaces 21 of these blocks being curved to 70 form continuations of the surfaces 16 and 17 of the body. The inner surfaces 22 of these jamb-blocks are flat. The line-spacing wheel 23 is a ring having a cylindrical inner surface 24, a cylindrical outer surface 75 25, crown teeth 26, and notches or depressions 27 in which fits the detent 28 (Fig. 6). A cylindrical case 29 is affixed to the end of the platen by screws 30.

75 The line-spacing wheel extends into the case 29, the outer edge of which bears against the shoulder of the wheel at the inner ends of the notches 27, and the body of the clutch extends into and through the line-spacing wheel, the surfaces 16 and 17 85 of the body fitting loosely within the surface 24 of the wheel, and the flange 18 of the body being close to the wheel and surrounded by the crown teeth 26. Hence the wheel is loosely confined between the case 90 29 and the flange 18 so that either the wheel or platen may be separately turned on the platen-axis. The hub 12 of the body fits snugly on the part 3 of the platen-shaft to which it is fastened by screws 31, and the 95 block 5 is in the body, between the parts 14 and 15, the axis of the platen passing through the block. Balls 32 are contained in the recesses 13 in the body between the block 5 and the jamb-blocks 19 and 20, these 100 blocks and the sides of the recesses 13 forming ball-retaining walls, and the balls bear on the surfaces 6 of the block 5 and the flat faces 22 of the jamb-blocks. The bearing surfaces 6 of the block 5 slope very 105 slightly, so that the planes in which they lie meet at a point on the axis of the platen, remote from the clutch, the block being approximately a hundredth of an inch wider at the end 9 than it is next to the inner ends 110

of the projections 7. The bearing surfaces 22 of the jamb-blocks also slope, and the planes in which they lie meet at a point remote from the clutch on the axis of the platen, this point and the point at which the planes of the surfaces 6 meet being both on one side of the clutch.

The construction and arrangement of the parts described are such that normally the block 5 is pressed by the spring against the balls and they force the jamb-blocks tightly against the inner surface 24 of the line-spacing wheel, so that it and the platen are clutched together. Then the action of the block 5 on the balls is that of a wedge, and since this block or wedge is loose in the slots 4, so that the whole block is movable toward and from either ball, both balls and both jamb-blocks will be tightly held between the wedge and the surface 24, even if one ball is slightly larger than the other, or if one jamb-block is slightly thicker than the other. Consequently this block or wedge is so movable, when it is forced by the spring to act on the balls, that it compensates automatically for small inequalities in the balls and jamb-blocks, such as are apt to exist and would be apt to have a bad effect on the action of the clutch unless the block or wedge could move transversely of the platen-axis.

The finger-wheel 33 of the platen is fast on a hub and sleeve or short shaft 34 which extends into the hollow part 3 of the platen shaft and is fastened therein by the screws 31, which pass through holes in the part 3 and bear at their inner ends against flattened parts of the shaft 34. A push-rod 35 extends loosely through the shaft 34 and into the recess 8 in the block 5, this push-rod having at its outer end a finger-button 36. In the hub 34 is a screw 37, and in the rod 35 are recesses 38 and 39 (Figs. 1 and 9) the inner ends of which co-act with the screw 37 to limit the axial movement of the rod.

To release the platen from the line-spacing wheel, and enable the platen to be separately rotated to any desired extent, the push-rod or releasing device is pressed inward until the outer end of the recess 38 in the rod is close to the screw 37. The rod may then be locked by turning it so as to bring the inner end of the recess 39 behind the screw. The push-rod forces the block 5 inward lengthwise of the common axis of the platen, line-spacing wheel and clutch, and the block rolls the balls axially of the platen and the clutch and from its head 11, and when the block is at the inner end of its movement where it exerts no pressure on the balls, the jamb-blocks 19 and 20 are loose, or else but lightly touch the line-spacing wheel, and either the platen or wheel may be separately rotated in either direction. When the push-rod is turned again, so as to bring the ends of the recess

38 into alignment with the screw 37, and the spring 10 is allowed to move the block 5 outward, the balls are rolled by the block toward the head 11 of the clutch and the jamb-blocks are forced by the balls tightly 70 against the line-spacing wheel, and thereafter the platen will be rotated by the line-spacing mechanism as though the spacing wheel were affixed immediately to the platen, this mechanism comprising, for example, a handle and a pawl such as are usually contained in Yost machines, the pawl being operative on the crown teeth 26 to turn the line-spacing wheel.

It will be understood that the invention 80 can be embodied in mechanism differing more or less in details of construction from that which has been described herein.

What I claim as new and desire to secure by Letters Patent, is:—

1. In a typewriting machine, comprising a cylindrical platen and a line spacing wheel separately movable on a common axis, a connecting rotary clutch including a pair of rollers and a device which extends between them and has opposite faces on which the rollers act when the platen and line spacing wheel are clutched together, said device being movable in the directions in which the rollers travel as they roll upon it, and being further movable bodily toward each roller when that roller is loose.

2. In a typewriting machine, comprising a cylindrical platen and a line spacing wheel separately movable on a common axis, a connecting clutch having ball-retaining walls, and including balls, each ball being between outer and inner walls the bearing surfaces of which slope toward points on said axis that are remote from and on one side of the clutch, and some of the walls being movable lengthwise of said axis and operative on the balls to roll them axially of the clutch.

3. In a typewriting machine, comprising a cylindrical platen and a line-spacing wheel separately movable on a common axis, a connecting rotary clutch including balls and a device on which the balls bear and through which said axis passes, said device being constrained to turn with the platen and being movable lengthwise and transversely of said axis and operative on the balls to roll them axially of the clutch.

4. In a typewriting machine, comprising a cylindrical platen and a line-spacing wheel separately movable on a common axis, a connecting rotary clutch including balls and a device on which the balls bear and through which said axis passes, the bearing surfaces of said device being in converging planes that meet at a point on said axis remote from the clutch and said device being constrained to turn with the platen and being movable lengthwise of said axis and opera-

tive on the balls to roll them axially of the clutch.

5. In a typewriting machine, comprising a cylindrical platen and a line-spacing wheel 5 separately movable on a common axis, a connecting rotary clutch including outer ball-retaining walls, a pair of balls, and a device which forms inner ball-retaining walls and through which said axis passes, the bearing 10 surfaces of said outer walls sloping toward a point on said axis remote from the clutch, and said device being movable lengthwise and transversely of said axis and operative on the balls to roll them axially of the 15 clutch.

6. In a typewriting machine, comprising a cylindrical platen and a line-spacing wheel separately movable on a common axis, a connecting rotary clutch including outer ball-retaining walls, a pair of balls, and a device which forms inner ball-retaining walls and through which said axis passes, the bearing surfaces of said outer walls and of 20 said device sloping toward points on said axis that are remote from and on one side of the clutch, and said device being movable lengthwise of said axis and operative on the balls to roll them axially of the clutch.

7. In a typewriting machine, comprising 25 a cylindrical platen and a line spacing wheel separately movable on a common axis, a connecting rotary clutch having ball-retaining walls, and including balls, a spring, and a releasing device, some of said walls being normally pressed against the balls by the 30 spring and being movable by the releasing device lengthwise of said axis and against the force of the spring to roll the balls axially of the clutch and being further movable transversely of said axis.

8. In a typewriting machine, comprising 35 a cylindrical platen and a line-spacing wheel separately movable on a common axis, a connecting clutch including balls, a block on which the balls bear and through which said axis passes and which is movable lengthwise and transversely of the axis, a spring that acts lengthwise of said axis, and a releasing device, the block being constrained to turn with the platen and being normally pressed against the balls by the 40 spring and being movable by the releasing device against the force of the spring to roll the balls axially of the clutch.

55 9. In a typewriting machine, comprising a cylindrical platen and a line spacing wheel 45 separately movable on a common axis, a connecting clutch including balls, a block which fits in longitudinal slots in the platen 50 shaft and on which the balls bear, a spring contained in the platen shaft and acting against the block, and a releasing device, the block being normally pressed against the 55 balls by the spring and being movable by

the releasing device against the force of the 65 spring to roll the balls axially of the clutch.

10. In a typewriting machine, comprising a cylindrical platen and a line-spacing wheel 60 separately movable on a common axis, a connecting clutch including a recessed body, jamb-blocks, balls, and a device on which the balls bear and through which said axis passes, the body being fast on the platen-shaft and surrounded by the line-spacing wheel, the jamb-blocks, balls and 70 said device being in the body, the balls being between the jamb-blocks and said device, and the jamb-blocks being between the balls and line-spacing wheel, and said device being movable lengthwise of said axis 75 and operative on the balls to roll them axially of the clutch.

11. In a typewriting machine, comprising a cylindrical platen and a line-spacing wheel 80 separately movable on a common axis, a connecting clutch including a recessed body, jamb-blocks, balls, and a device on which the balls bear and through which said axis passes, the body being fast on the platen-shaft and surrounded by the line-spacing 85 wheel, the jamb-blocks, balls and said device being in the body, the balls being between the jamb-blocks and said device, and the jamb-blocks being between the balls and line-spacing wheel, the bearing surfaces of said 90 device being in converging planes that meet at a point on said axis remote from the clutch, and said device being constrained to turn with the platen and being movable lengthwise of said axis and operative on the 95 balls to roll them axially of the clutch.

12. In a typewriting machine, comprising a cylindrical platen and a line-spacing wheel 100 separately movable on a common axis, a connecting clutch including a recessed body, jamb-blocks, balls, and a device on which the balls bear and through which said axis passes, the body being fast on the platen-shaft and surrounded by the line-spacing 105 wheel, the jamb-blocks, balls and said device 110 being in the body, the balls being between the jamb-blocks and said device, and the jamb-blocks being between the balls and line-spacing wheel, the inner bearing-surfaces of the jamb-blocks sloping toward a point on 115 said axis remote from the clutch, and said device being movable lengthwise of said axis and operative on the balls to roll them axially of the clutch.

13. In a typewriting machine, comprising 120 a cylindrical platen and a line-spacing wheel 125 separately movable on a common axis, a connecting clutch including a recessed body, jamb-blocks, balls, and a device on which the balls bear and through which said axis passes, the body being fast on the platen shaft and surrounded by the line spacing 130 wheel, the jamb-blocks, balls and said device

- being in the body, the balls being between the jamb-blocks and said device, and the jamb-blocks being between the balls and line-spacing wheel, the bearing surfaces of said device and the inner bearing-surfaces of the jamb-blocks sloping toward points on said axis that are remote from and on one side of the clutch, and said device being movable lengthwise of said axis and operative on the balls to roll them axially of the clutch. 14. In a typewriting machine, comprising a cylindrical platen and a line-spacing wheel separately movable on a common axis, a connecting clutch including a recessed body, jamb-blocks, balls, a central block on which the balls bear and through which said axis passes, a spring that acts lengthwise of said axis, and a releasing device, the body being fast on the platen-shaft and surrounded by the line-spacing wheel, the jamb-blocks, balls and said central block being in the body, the balls being between the jamb-blocks and said central block, and the jamb-blocks being between the balls and line-spacing wheel, and said central block being normally pressed against the balls by the spring and being movable by the releasing device against the force of the spring to roll the balls axially of the clutch. 15. In a typewriting machine, comprising a cylindrical platen and a line-spacing wheel separately movable on a common axis, a connecting clutch including a recessed body, jamb-blocks, balls, a central block on which the balls bear and through which said axis passes, a spring that acts lengthwise of said axis, and a releasing device, the body being fast on the platen-shaft and surrounded by the line-spacing wheel, the jamb-blocks, balls and said central block being in the body, the balls being between the jamb-blocks and said central block, and the jamb-blocks being between the balls and line-spacing wheel, the bearing surfaces of said central block and inner bearing-surfaces of the jamb-blocks sloping toward points on said axis that are remote from and on one side of the clutch, and said central block being normally pressed against the balls by the spring and being movable by the push rod against the force of the spring to roll the balls axially of the clutch. 16. In a typewriting machine, comprising a cylindrical platen and a line-spacing wheel separately movable on a common axis, a connecting clutch including balls, a block on which the balls bear and through which said axis passes, a spring that acts lengthwise of said axis, and a push-rod which projects from the platen shaft, the block being normally pressed against the balls by the spring and movable by the push-rod against the force of the spring to roll the balls axially of the clutch. 17. In a typewriting machine, comprising a cylindrical platen and a line-spacing wheel separately movable on a common axis, a connecting clutch including a recessed body fast on the platen-shaft, jamb-blocks, balls, a central block on which the balls bear and through which said axis passes, a spring that acts lengthwise of said axis, and a push rod projecting from the platen-shaft, the line-spacing wheel surrounding the body and fitting loosely in a cylindrical case affixed to the platen, the jamb-blocks, balls and said central block being in the body, the balls being between the jamb-blocks and said central block, and the jamb-blocks being between the balls and line-spacing wheel; the bearing surfaces of said central block and inner bearing-surfaces of the jamb-blocks sloping toward points on said axis that are remote from and on one side of the clutch, and said central block being normally pressed against the balls by the spring and being movable by the push rod against the force of the spring to roll the balls axially of the clutch. 18. In a typewriting machine, comprising a cylindrical platen and a line spacing wheel separately movable on a common axis, a connecting rotary clutch including a pair of rollers and a device which extends between them and has opposite faces on which the rollers act when the platen and line spacing wheel are clutched together, and which fits loosely in an opening in the platen shaft, said device being movable in the directions in which the rollers travel as they roll upon it, and being further movable bodily toward either roller when that roller is loose. 19. In a typewriting machine, the combination of a platen, a line spacing wheel, and a connecting clutch, said clutch comprising a pair of rollers and an intermediate loosely mounted self-adjusting double wedge capable of movement both longitudinally and transversely of the platen. 20. Signed at Syracuse, in the county of Onondaga, and State of New York, this fifteenth day of April, A. D. 1914.
